UNITED STATES PATENT OFFICE.

EDSON F. GALLAUDET, OF NORWICH, CONNECTICUT.

AEROPLANE.

1,200,098.

Specification of Letters Patent.

Patented Oct. 3, 1916.

Application filed April 4, 1914. Serial No. 829,471.

To all whom it may concern:

Be it known that I, EDSON F. GALLAUDET, a citizen of the United States, and a resident of the town of Norwich, in the county 5 of New London and State of Connecticut, have invented certain new and useful Improvements in Aeroplanes, of which the following is a specification.

This invention relates to flying machines 10 of the aeroplane type, and more particularly to the construction of the outer end portions of the wings or main sustaining planes of such machines.

In a prior application, filed July 25, 1913, 15 Serial No. 781,089, I have shown and described a wing structure in which movable tips are so mounted upon the flexible outer ends of the wings and operatively connected that the tip on one side can be extended and 20 that on the other side simultaneously withdrawn to produce differential changes both in the area and the center of pressure of the wings on opposite sides of the machine.

One object of my present invention is to 25 increase the efficiency of the tips, by changes in their construction, sufficiently to render them capable of maintaining the lateral balance of the machine without the supplemental action of flexible outer wing portions, and another object is to simplify the 30 construction and especially the connection between the tips and the outer ends of the wings.

To this end the invention comprises certain 35 novel features of construction, arrangement, and combinations of parts as herein-after described and particularly pointed out in the appended claims.

In the accompanying drawings, which 40 form a part of this specification, Figure 1 is a plan view of a monoplane flying machine, with a part of the outer covering of one of the wings broken away, illustrating in combination the several features of my invention, and Figs. 2 and 3 are sections of a tip 45 on the line 2 2 and 3 3, respectively, of Fig. 1.

Referring to the drawings, the machine 50 comprises, as its principal parts, a body B, with the usual fixed tail planes F F', hinged elevating planes E E', and rudder R, and, suitably mounted thereon, the wings W W', with the movable tips T T'.

As here illustrated, the framework of each 55 wing W W' comprises two tubular transverse spars 1 and 2, connected at their outer

ends by a diagonal brace 3, a series of preferably curved fore and aft ribs 4, and front and rear edge pieces 5 and 6. The edge pieces extend parallel to each other at the inner 60 ends of the wings and then are preferably bent so as to incline toward each other at a slight angle, while the front edge piece is further bent near the outer end of the wing, so as to incline rearwardly at a somewhat 65 greater angle. This framework is covered above and below (the lower surface not shown) with the usual or any suitable surfacing material 7 for the greater portion of its length and, preferably, at its outer end, 70 with aluminum or other thin light metallic plates 8 which are stiffened by outer fore and aft ribs 9 and marginal rib 10, forming a wing structure which tapers toward its outer end and fore and aft is convex above 75 and slightly concave below.

The tips T and T' are suitably framed and covered above and below (the lower surface not shown), preferably with metallic plates 11 of aluminum at their inner ends and at 80 their outer ends with the usual surface covering 12. They are more or less triangular in shape and are curved from front to rear to form a convex upper surface and a slightly concave lower surface (see Fig. 3) 85 and also upwardly, or are inclined upwardly at an angle, from near their inner to their outer ends (see Fig. 2). These tips are pivotally mounted, one at the end of each wing, between the stiffened surface 90 plates of the wings, upon suitable bearings 13, provided therefor at the outer ends of the rear transverse spars 2, to swing forward and back in the plane of the wings; and they are connected, as by pivoted links 95 14, with any suitable mechanism (not shown) by which the operator can, from his seat within the body of the machine, simultaneously cause them to swing in opposite directions, one outwardly and forwardly and the other rearwardly and inwardly.

The advantages of tips constructed and operatively mounted as described will readily be understood by those skilled in the art. 105 The swinging forward of the tip on one side of the machine will, without changing the area or the angle of incidence of the wing surface, increase the lifting power of the under surface of that tip, both by 110 reason of its movement outwardly so that it acts on a longer lever arm and thereby shifts

the center of pressure toward that side and because this movement brings its concave lower surface into a position where it becomes efficient, and decrease the depressing effect of its curved or inclined upper surface, while the simultaneous withdrawal of the tip on the other side of the machine will similarly decrease the lifting power of its under surface and increase the depressing effect of its upper surface. Furthermore, when in flight the machine tilts laterally and commences to sideslip, the tip of the depressed wing, especially if extended, will present a positive angle of incidence in the direction in which the machine is slipping while the tip of the other wing will present a negative angle of incidence in the same direction, thereby instantly righting the machine and checking the slipping movement.

While I have shown and described my invention in the form which I now consider the best for its embodiment, it will be understood that it can be variously modified in its several details, within the scope of the appended claims, without departing from the spirit or sacrificing the advantages thereof.

What I claim as new, and desire to secure by Letters Patent, is—

1. In a flying machine, a wing structure comprising a main wing tapering rearwardly at its outer end which is framed and covered above and below, at its outer end with metallic plates, and a tapering tip which is framed and covered above and below and which at its inner end, covered with metallic plates, is pivoted between the covering plates at the tapering outer end of the wing to form a movable extension thereof.

2. In a flying machine, a wing structure comprising a main wing tapering rearwardly at its outer end which is framed and covered above and below, at its outer end with thin metallic plates strengthened with fore and aft ribs on their outer surfaces, and a tapering tip which is framed and covered above and below and which at its inner end, covered with thin metallic plates, is pivoted between the strengthened covering plates at the tapering outer end of the wing to form a movable extension thereof.

3. In a flying machine, a wing structure comprising a main wing which in fore and aft section is convex above and concave below and has a tapering outer end covered above and below with metallic plates and, pivoted to the outer end of the wing to swing between its covering plates, a tapering tip which in fore and aft section is convex above and concave below and is upwardly inclined at its outer end.

4. In a flying machine, a wing structure comprising a framed and covered wing which in fore and aft section is convex above

and concave below and has the outer portion of its front edge rearwardly inclined to form a tapering outer end and, pivotally mounted at its inner end to the outer end of the wing between the upper and lower surface coverings, a framed and covered tapering tip which in fore and aft section is convex above and concave below and is curved upwardly at its outer end.

5. In a flying machine, a wing structure comprising a framed and covered wing which in fore and aft section is convex above and concave below and has the outer portion of its front edge rearwardly inclined to form a tapering outer end and, pivoted to swing between the upper and lower coverings and forming at all times a substantially unbroken extension of the outer end of the wing, a framed and covered tapering tip which in fore and aft section is convex above and concave below and is upwardly inclined at its outer end and which is adapted to swing outward and forward until its front edge is substantially in line with the inclined portion of the front edge of the wing and backward and rearward until its outer end is substantially behind its inner end.

6. In a flying machine, a wing structure comprising a framed and covered wing having a tapered outer end and a tapering tip which is upwardly inclined at its outer end and centrally of its inner end is pivotally mounted between the upper and lower surface coverings at the end of the wing and which constitutes a substantially unbroken extension of the tapered outer end of the wing.

7. In a flying machine, a wing structure comprising a framed and covered wing having a tapered outer end and a tapering tip which is upwardly inclined at its outer end and centrally of its inner end is pivotally mounted between the upper and lower surface coverings at the outer end of the wing and which, normally held in intermediate position, is adapted to swing forward until its front and rear edges are substantially in line with the tapering outer portions of the front and rear edges of the wing and backward until its outer end is substantially behind its pivoted inner end.

8. In a flying machine, a pair of wings which are mounted on opposite sides thereof and are covered above and below at their outer ends with metallic plates, tips which are upwardly inclined at their outer ends and at their inner ends are pivotally mounted between the upper and lower covering plates at the outer ends of the wings and which, normally held in intermediate position, are adapted to swing forward until they are substantially in line with the outer ends of the wings and backward until their outer ends are substantially behind their pivoted inner ends, and means for simultane-

ously swinging the tips of the two wings in opposite directions to and from normal position.

9. In a flying machine, a pair of wings, 5 mounted on opposite sides thereof, which at their outer ends are tapered rearwardly and covered above and below with metallic plates, tapering tips which are upwardly inclined at their outer ends and centrally of 10 their inner ends are pivotally mounted between the upper and lower covering plates at the outer ends of the wings and which, normally held in intermediate position, are

adapted to swing forward until their front and rear edges are substantially in line with 15 the tapering outer portions of the front and rear edges of the wing and backward until their outer ends are substantially behind their pivoted inner ends, and means for simultaneously swinging the tips of the two 20 wings in opposite directions to and from normal position.

EDSON F. GALLAUDET.
